(57) **CLAIM**

The ornamental design for a brewer, as shown and described.

DESCRIPTIONFIG. 1 is a perspective view of our new design;
FIG. 2 is a front elevational view thereof;
FIG. 3 is a left side elevational view thereof,
FIG. 4 is a right side elevational view thereof;
FIG. 5 is a rear elevational view thereof;
FIG. 6 is a top view thereof; and,
FIG. 7 is a bottom view thereof.

The broken lines shown in the drawings are for purposes of illustrating portions of the design and form no part of the claimed design.
